FEEDING MECHANISM

August E. Almgren, Hillside, N. J., assignor to
American Can Company, New York, N. Y., a
corporation of New Jersey

Application July 19, 1944, Serial No. 545,702

6 Claims. (Cl. 198—25)

This invention relates to a feeding mechanism for containers or other articles and has particular reference to a rotatable feed or transfer turret for separating individual articles from a stack of articles confined within a magazine while holding back or otherwise supporting the remaining articles in the stack and for moving the separated articles gradually into an advanced position.

In the separation of containers which are fed usually by gravity from the bottom of a vertically disposed stack or a magazine, the supply of containers suddenly drops when the lowermost container is withdrawn. This sometimes results in marring or damaging the containers particularly when such containers are fragile. The continuous dropping of containers in a magazine also causes considerable noise especially when they are made of metal.

The instant invention contemplates overcoming these difficulties by the provision of a transfer turret which can be mounted on a horizontal shaft located beneath a magazine and which carries devices for supporting and gradually lowering the supply of containers while separating the lowermost container from the remainder as an incident to transferring it to a suitable place of discharge.

An object of the invention is the provision of a rotatable transfer turret having pockets for receiving the lowermost container from a supply of containers in a magazine while supporting and moving all of the containers to separate the lowermost container and to transfer it to a place of discharge.

Another object is the provision of such a transfer turret having arms which define pockets for receiving containers for separation and transfer, wherein one wall or arm of each pocket is movable in advance of the other to engage beneath the supply of containers in the magazine and to function as a platform for supporting the containers while moving them downwardly to an advance position at which time both walls of the pocket coact to separate the lowermost container and to transfer it to a suitable place of discharge.

Numerous other objects and advantages of the invention will be apparent as it is better understood from the following description, which, taken in connection with the accompanying drawings, discloses a preferred embodiment thereof.

Referring to the drawings:

Figure 1 is a front elevational view of a feeding mechanism embodying the instant invention, with parts broken away;

Fig. 2 is a sectional view of the mechanism illustrated in Fig. 1 as taken substantially along the line 2—2 in that figure;

Fig. 3 is a sectional view taken substantially along the broken lines 3—3 in Fig. 2 with parts broken away;

Figs. 4 and 5 are sectional views taken substantially along the broken lines 4—4 in Fig. 2, showing the parts in different positions; and

Fig. 6 is a perspective view of certain parts of the feeding mechanism with parts broken away and with parts in section.

As a preferred embodiment of the instant invention the drawings illustrate a feeding mechanism for separating fibre milk containers A individually from the bottom of a stack of such containers and for advancing them in timed order to a suitable place of deposit. The containers illustrated are square in cross-section and are arranged in the stack in a horizontal position although the invention is equally well adapted to containers of other shapes.

The feeding mechanism may be a portion of a more elaborate machine in which the containers are received in a continuous procession from another machine. The containers are received in a vertical magazine B (Fig. 1) and are fed individually from the bottom of the magazine by a continuously rotating turret C disposed vertically adjacent the magazine.

The turret C carries a plurality of fixed arms D and E equally spaced around its periphery and an equal number of movable arms F which are disposed adjacent the fixed arms. The movable arms F normally cooperate with the fixed arms D and E (see also Fig. 6) in forming right angular shaped pockets G for the reception of individual containers from the magazine B.

During a cycle of rotation of the turret C and as a set of the fixed arms D and E and the movable arms F approach the magazine B, the movable arms F shift away from its fixed arms to a position in advance thereof and move under the stack of contains in the magazine, engaging horizontally under the container next above the lowermost container in the stack and serving as platforms for the stack. In this manner the movable arms support the stack while the lowermost container is removed by a preceding set of 50 the arms.

As the turret C continues to rotate, the movable arms F supporting the stack and moving with the turret, travel through an outward and downward path, and thus lowers the stack a distance equal to one container. This movement

brings the lowermost container in the stack into a position below and clear of the magazine. The lowering action is effected smoothly and gradually so as to prevent damaging of the containers by sudden falling.

During this lowering of the stack, the fixed arms D and E of the turret travel through an arc toward the stack and come into engagement with the lowermost container just as the stack reaches its fully lowered position, the fixed arms and the movable arms then being in the normal position of forming a right angle pocket around the container. The arms forming the pocket confine the container on two sides. With the container thus seated in its pocket continued rotation of the turret brings the next succeeding movable arms F into position under the container next above to support the stack as just explained while the turret separates the confined container from the remainder of the stack and carries it downwardly through a curved path of travel to any suitable place of deposit.

A detailed description of the feeding mechanism will now be given. The various working parts of the mechanism are supported on a hollow side frame 21 which constitutes the main frame. This frame serves as a casing or housing for protecting various driving elements of the machine located within the frame as well as for supporting parts on its exterior surface.

The magazine B is one of the parts that is supported on the outside of the frame 21 and is secured to the front wall thereof. This magazine comprises a casting 22 (Figs. 1, 2 and 3) of integral ribs and webs setting off and surrounding a vertical rectangular shaped passageway 23 open at its top and bottom ends for the reception of and the passage therethrough of the containers A. Four angle iron guide bars 24 secured to the top of the casting adjacent the corners of the passageway are used to guide the containers into the magazine.

The turret C is disposed immediately below the magazine B and to one side thereof, toward the left as viewed in Fig. 1. This turret comprises in part a starwheel 27 on which the fixed arms D are or may be integrally formed. The drawings show four of these fixed arms. Each arm is formed with a flat, straight container engaging face 28. It is these faces that form one side of the pockets G hereinbefore mentioned.

The starwheel 27 is formed on the outer end of a long hub 31 (Figs. 2 and 6) which is mounted for rotation on a shouldered horizontal shaft 32 secured in a boss 33 formed on a cover plate 34 bolted in place over a clearance opening 35 in the rear wall of the main frame 21. The shaft is held stationary. A head 36 on the outer end of the shaft retains the turret in place on the shaft.

The inner end of the starwheel hub 31 is formed with a disc 38 having an inwardly projecting flange 39 which fits loosely within a clearance opening 41 in the front wall of the main frame 21. The disc forms a rotatable cover plate for the opening.

The entire turret unit, including its starwheel, hub, and flanged disc is rotated continuously by a ring gear 44 which is bolted to the inner edge of the flange 39 on the turret disc 38. The ring gear meshes with an idler gear 45 (see also Fig. 3) located within the main frame 21. This idler gear is mounted on a short shaft 46 journaled in a pair of spaced bearings 47 formed on the front and rear walls of the frame. The idler gear is

driven continuously by a main driving gear 48 which is journaled in the main frame and rotated in any suitable or desired manner.

The fixed arms E of the turret are disposed intermediate the starwheel 27 and the turret disc 38 and are formed as separate members which are bolted to the turret hub 31. Each arm preferably is made from strap iron which is bent to provide a flat straight face 49 disposed in transverse alignment with the fixed arm D to coact therewith in forming a pocket G.

The movable arms F carried in the turret C for cooperation with the fixed arms D and E in removing containers from the magazine as hereinbefore explained, are formed on horizontally disposed sleeves 51 (Figs. 2, 3 and 6) which surround and are secured to actuating shafts 52. These shafts are carried in bearings 53 formed in the starwheel 27 and in bearings 54 formed in the turret disc 38. There are four sleeves 51, one located adjacent each pair of fixed arms D and E on the turret starwheel.

Each sleeve 51 carries two movable arms F, one located adjacent the turret disc and the other adjacent the starwheel. The movable arm disposed adjacent the starwheel is bent outwardly into the vertical plane of the wheel where it is in alignment with the fixed arms. Each movable arm is formed with a flat, straight face 56 which is disposed at right angles to the faces 28 and 49 of the fixed arms when the movable arms are in their normal position and thus sets off the pockets G hereinbefore mentioned for the reception of individual containers. The outer ends of the faces 56 are formed with a bevel 57 to facilitate insertion of the arms under the stack as hereinbefore mentioned. The movable arms are maintained in their normal position and are actuated into stack supporting position by a cam device H (Fig. 6) which will now be explained.

The movable arm actuating device H controls the movement of all of the arm actuating shafts 52. For this purpose the inner end of each actuating shaft carries a segmental pinion 61 (Figs. 2, 4, 5 and 6) which meshes with segmental gears 62 formed on cam levers 63 mounted on short shafts 64 journaled in suitable bearings formed in the turret disc 38. There are four cam levers 63, one for each pair of movable arms F, and each lever carries a cam roller 65. All of these cam rollers operate in a single cam groove 66 formed in a stationary face cam 67 mounted on the turret shaft bearing 33 of the cover plate 34.

Hence as the turret C rotates, it carries the cam levers 63 mounted on the turret disc, through a circular path of travel and causes the cam rollers 65 to traverse the cam groove 66. This travel of the cam levers and the shape of the cam rocks the levers and thus rotates the meshed gears 62 and pinions 61, effecting an oscillating movement of the shafts 52 which carry the movable arms F. It is this oscillation of the shafts 52 that shifts the movable arms F away from their associated fixed arms D and E to engage under and support the stack of containers in the magazine as hereinbefore explained. It is also these same devices that are effective in retarding the movement of the arms F while they are in stack supporting position so that the fixed arms D and E of the turret catch up with the movable arms to form between them a right angle pocket G for the reception and separation of the lowermost container from the others in the stack.

In forming these pockets the two movable arms F of each sleeve 51, the one adjacent the turret

disc 38 and the other adjacent the starwheel 21 cooperate in supporting a container near its opposite ends to hold it in a horizontal position. The other side of the pocket is formed by the fixed arm D of the starwheel 21 which engages the container near its outer end and by the fixed arm E which engages the container intermediate the movable arms F.

Provision is made for insuring full seating of a container A in a pocket G of the turret C as the fixed arms D and E come into engagement with the lowered container. For this purpose the magazine B is provided with a yieldable depending guide shoe 71 which forms an extension of one side of the magazine. The shoe comprises two separate spaced and parallel prongs extending down adjacent the length of the lowermost container. These prongs are disposed opposite the turret C. The prongs depend from a hub 72 mounted on a horizontally disposed pivot pin 73 rotatably carried in a bearing boss 74 formed on the lower end of the magazine B. The pivot pin extends into the interior of the hollow main frame 21 and carries on its inner end a rocker lever 75 (see Figs. 4 and 5).

The rocker lever 75 carries a cam roller 76 which operates against an edge cam 77 formed on the periphery of the flange 39 of the turret disc 38. This cam is formed with four high spots or projections 78, located in relation to each of the four fixed arms D of the turret C. The cam roller is maintained in operative engagement with the cam by a tension spring 79, one end of which is connected to a lug 81 formed on the rocker lever. The other end of the spring is hooked over a stationary pin 82 secured in the front wall of the main frame 21 (see Fig. 2).

Hence when a pair of the fixed arms D and E of the turret come into engagement with the side of a lowered container A to remove it from the stack, it first presses the container against the prongs of the guide shoe 71 and this seats the container fully in the pocket. Immediately following this seating operation a high spot 78 of the edge cam 77 forces the rocker lever 75 outwardly and this movement rocks the guide shoe outwardly away from the container so that undue pressure on the container as it starts its circular path of travel with the turret, will be relieved.

During the travel of a container through its downward curved path of travel toward a place of deposit, it is maintained in position within its turret pocket G by a pair of spaced and parallel curved guide rails 85 (Figs. 1, 2 and 3) which extend down adjacent the path of travel of the container. These guide rails are tied together transversely by integrally formed spacer members 86 so as to form a unitary structure. This guide rail structure is bolted to the front wall of the main frame 21.

The containers are further retained in their turret pockets against endwise displacement by a curved end guide rail 87 which is disposed adjacent the path of travel of the container and which engages the outer end of the container. The inner end of the container lightly engages against the turret disc 38. This end guide rail is secured to the bottom of the magazine B and to the outer guide rails 85.

The outer guide rails 85 terminate adjacent the bottom of the turret C. Hence when a container reaches this point in its travel it falls from its turret pocket G to any suitable place of deposit. By way of example, a movable cradle 88 (Fig. 1) mounted on a reciprocable stroke bar 89 is shown

in the drawings as a receiver for the discharged container, although any other form of device may be used to carry the container to any suitable place of deposit.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a feeding mechanism for separating containers from a magazine and for transferring them to a place of discharge, the combination of a magazine for holding a supply of containers, a rotatable transfer turret having a pocket for receiving a container from said magazine, a stationary arm and a movable arm carried on said turret and together forming said pocket, means actuated by the rotation of the turret for shifting said movable arm away from said stationary arm to constitute said movable arm as a platform for engagement against the outermost container of the supply of containers in said magazine for temporarily supporting said supply of containers, the rotation of the turret also engaging said stationary arm against the outermost container supported in the magazine to separate said outermost container from the remaining containers to remove it from said magazine while the remaining containers in the magazine are supported by said movable arm, said movable arm shifting means being further operable to return said movable arm to its pocket forming position relative to said stationary arm when said movable arm ceases to function as a platform support for the containers remaining in said magazine.

2. In a feeding mechanism for separating containers from a magazine and for transferring them to a suitable place of discharge, the combination of a magazine for holding a vertical stack of containers, a rotatable transfer turret mounted on a horizontal shaft adjacent the magazine, pockets in said turret for receiving containers from said magazine comprising a plurality of stationary arms and a plurality of cooperative movable arms, means for shifting a said movable arm away from its associated stationary arm to provide a platform for engagement beneath the lowermost container in said stack of containers in said magazine and for temporarily supporting and lowering said stack, and actuating means effective in rotating said turret for moving a said stationary arm against the lowermost container of the stack supported on said movable arm to separate said container from the other containers and to transfer it from said magazine, said movable arm shifting means returning a said movable arm to its pocket forming position relative to a said stationary arm when said movable arms cease to support the containers remaining in said magazine.

3. In a feeding mechanism for separating containers from a magazine and for transferring them to a suitable place of discharge, the combination of a magazine for holding a supply of containers, a rotatable transfer turret having pockets for receiving containers from said magazine, a plurality of stationary arms and a plurality of cooperative movable arms carried on said turret and forming said pockets, a corresponding lever for each movable arm also carried on said

turret, a cam for effecting movement of said levers to shift a said movable arm away from its associated stationary arm to provide a platform for engagement beneath the lowermost container of a supply of containers in said magazine and to temporarily support said magazine held containers, and actuating means effective in rotating said turret for bringing a said stationary arm against the said lowermost container to separate and to transfer it from said magazine, said cam and said levers also effecting the return movement of a said movable arm to its pocket forming position when said arm ceases to support the containers remaining in said magazine.

4. In a feeding mechanism for separating containers from a magazine and for transferring them to a suitable place of discharge, the combination of a magazine for holding a supply of containers, a rotatable transfer turret having pockets for receiving containers from said magazine, a plurality of stationary arms and a plurality of cooperative movable arms carried on said turret and forming said pockets, means for shifting said movable arms away from said stationary arms while both are moved with the rotating turret and to provide a forward platform engaging beneath and supporting the lowermost container of the supply of containers in said magazine while a succeeding platform provides a support for the rest of the containers in the magazine, and actuating means effective in rotating said turret for moving a said stationary arm against the lowermost container supported in the magazine to separate said container from the other containers and to transfer it from said magazine, said movable arm shifting means returning said movable arms to pocket forming positions when they cease to support the containers remaining in said magazine.

5. In a feeding mechanism for separating containers from a magazine and for transferring them to a suitable place of discharge, the combination of a magazine for holding a supply of containers, a rotatable transfer turret having pockets for receiving containers from said magazine, a plurality of stationary arms and a plurality of cooperative movable arms carried on said turret and forming said pockets, means for shifting a said movable arm away from its asso-

ciated stationary arm to provide a platform for engagement beneath the lowermost container of a supply of containers in said magazine and to temporarily support said magazine held containers, actuating means effective in rotating said turret for moving a said stationary arm against the lowermost container supported in the magazine to separate said container from the other containers in the magazine, and a yieldable shoe disposed adjacent said magazine for holding the said lowermost container against said engaging stationary arm as the container is being separated to fully seat the container in its turret pocket, said movable arm shifting means returning a said movable arm to its pocket forming position relative to its associated stationary arm when said movable arm ceases to support the containers remaining in said magazine.

6. In a feeding mechanism for separating containers from a magazine and for transferring them to a suitable place of discharge, the combination of a magazine for holding a supply of containers, a rotatable transfer turret having pockets for receiving containers from said magazine, a plurality of stationary arms and a plurality of cooperating movable arms carried on said turret and forming said pockets, means for shifting a said movable arm away from its associated stationary arm to provide a platform for engagement beneath the lowermost container of a supply of containers in said magazine and to temporarily support said magazine held containers, actuating means effective in rotating said turret for moving a said stationary arm against the lowermost container supported in the magazine to separate said container from the other containers in the magazine, a yieldable shoe disposed adjacent said magazine for holding the said lowermost container against said engaging stationary arm as the container is being separated to fully seat the container in its turret pocket, and means for moving said shoe out of engagement with a container after seating it in its pocket, said movable arm shifting means returning a said movable arm to its pocket forming position relative to its associated stationary arm when said movable arm ceases to support the containers remaining in said magazine.

AUGUST E. ALMGREN.
